UNITED STATES PATENT OFFICE.

DANIEL MANSON SUTHERLAND, JR., OF TRENTON, NEW JERSEY.

ELECTRIC INSULATION BOARD AND METHOD OF MAKING SAME.

No Drawing.

Application filed November 6, 1923. Serial No. 673,221.

To all whom it may concern:

Be it known that I, DANIEL MANSON SUTHERLAND, Jr., a subject of the King of Great Britain (who has filed his first papers and declared his intention of becoming a citizen of the United States), now residing at Trenton, in the county of Mercer and State of New Jersey, have invented certain new and useful Improvements in Electric 5 Insulation Boards and Methods of Making Same, of which the following is a specification.

This invention pertains to electric-insulation boards and bodies, and to the method 10 of producing the same.

The purposes sought and attained by the invention are the production of an inexpensive electric-insulation board or body of high insulating capacity, of desired color or 15 shade, and capable of receiving and maintaining any desired finish.

To these ends the invention consists in forming a sheet or body of pulp or cellulose, combined with gilsonite, asphaltum, mineral 20 pitch, elaterite, resin, or other usual binder; drying the same to a suitable degree; then applying to its face or faces a thin coating or layer of a cellulose acetate varnish or lacquer produced with the aid of a suitable 25 solvent and thinning agent; and subjecting the sheet or body to compression and heat.

The primary purpose of the cellulose varnish or lacquer coating is to prevent the insulating body, board or other, from adhering 30 to the contacting faces of a press, mold, or other structure in which the final compression and drying under heat are effected; also to permit or facilitate the incorporation 35 of any suitable pigment or coloring agent, and to produce a surface which may be finished by the aid of sandpaper, emery cloth, or other abradant of suitable fineness, or by 40 buffing or like treatment where a high polish as distinguished from a dead or flat finish, is desired. The boards or bodies so produced 45 are also devoid of stickiness or tackiness, and hence are not liable to adhere to one another, or to their wrappings, when packed or shipped.

50 No special form or construction of apparatus is required in carrying out my process. On the contrary, usual types of presses, molds, etc., for extracting surplus moisture and for shaping and compressing the body 55 and completely drying the same, may be em-

ployed. After such final compression and drying the surface may be finished after the manner of finishing various woods and compositions, either through the use of abrasives and powders suitable to the production 60 of a smooth surface without high polish, or gloss, or a highly polished surface.

Better to explain the present invention, and to differentiate the method of treatment or manufacture from prior practice, it may 65 be stated that in the process of manufacturing insulation boards composed of pulp and gilsonite or other binder, it is necessary to compact the composition in a press or mold provided with pressure heads, plates or 70 walls, one or more, capable of being heated and cooled in some convenient way. Where the composition contains gilsonite, or any one of a number of other binders, difficulty is experienced in compacting the composition 75 owing to its stickiness or tendency to adhere to contacting surfaces. Various attempts have been made heretofore to prevent such adherence to the press or mold surfaces, but so far as I am aware they have failed 80 to accomplish the desired result, and have likewise resulted in producing a body the surface of which is itself sticky or tacky, and difficult to finish satisfactorily or in a manner acceptable to the trade. 85

Various agents or compositions designed to overcome the stated difficulty have been found to impair the dielectric properties of the finished board. This is true, for instance, of collodion or nitrocellulose varnishes, since a short circuit or a flash-over 90 is liable to cause combustion. Surface coatings consisting mainly of fatty acids, of linseed or china wood oil, or coatings similar to oil varnishes, prevent stickiness in some 95 measure but fail to give a satisfactory finish or surface.

I have found through careful experimentation that varnishes or lacquers made from cellulose acetate dissolved in a suitable solvent give a film on the surface which prevents stickiness under combined heat and pressure, and at the same time, through close union with the pulp or cellulose body or composition, affords a surface that can be 100 sanded or buffed to a fine finish, either flat or of high polish.

It is desirable in many instances to impart to the board or body a degree of flexibility, or a capability of being bent to 110

greater or less extent. This characteristic may be secured through the employment of softening agents added to the cellulose acetate or like film in varying proportions according to the degree of flexibility desired.

So, too, coloring matter may be incorporated in the cellulose acetate varnish to give various colors which are not obtainable when dark-colored oil varnishes or similar materials are used. The cellulose acetate varnish or lacquer unites, as above indicated, with the cellulose composition of the board or body, during compression and heating, and causes the color to penetrate or permeate said body to a greater or less depth, thus making a better commercial product than would be produced if the coloring matter were confined to a thin surface film or coating.

As indicated, the selection of a proper cellulose acetate lacquer or varnish is important. I have found, for instance, that the hydracetate of cellulose gives better results than the triacetate of cellulose, because it is more stable than the latter and is more readily soluble in cheaper solvents. The principal solvents used are acetone and methylacetone, but the latter can be used successfully only in conjunction with hydracetate, as it will not, alone, completely dissolve the triacetate.

The proportion of solvent used depends upon the method of applying the lacquer. For example, when the lacquer is applied by dipping the board or article, it is expedient to employ twelve (12) parts of methylacetone to one (1) part of cellulose hydracetate, whereas but eight (8) parts of solvent to one (1) part of acetate are used when the coating is applied by means of a brush.

To prevent the film or coating from becoming brittle, use may be made of methyl ester of paratoluylsulphoneamide, triacetin, or triphenyl phosphate. The use of methyl ester of paratoluylsulphoneamide is preferred, as triacetin and triphenyl phosphate give less satisfactory results. Care must be taken in the use of any softening agent or solvent that the quantity employed be not excessive, as otherwise it effloresces on the surface of the product, causing a white or moldy appearance thereon. One (1) part of methyl ester of paratoluylsulphoneamide to ten (10) parts of hydracellulose is sufficient to prevent brittleness and does not cause efflorescence, whereas one (1) part of said methyl ester to five (5) parts hydracetate causes efflorescence which materially mars the appearance of the product.

When desired, the hydracetate solution may be diluted through the addition of ethyl-alcohol and benzol, but such agents must be used only in limited quantity, as otherwise the hydracetate is thrown out of

solution. A thinning composition composed of two (2) parts of methylacetone, one (1) part ethyl-alcohol, and one (1) part of benzol gives satisfactory results. These proportions may be varied within reasonable limits without precipitating the hydracetate of cellulose out of the solution, but undue variation must be avoided else such precipitation will occur.

To produce various colored surfaces, coloring matter may be added to the hydracetate solution in suitable quantity to give the desired color or shade, but the pigment or coloring matter must be such as will withstand the temperature of the heating plates, and be as stable as possible when subjected to strong light. For producing a black finish or color, nigrosome is the most suitable agent at present known to me. Carbon black may be used, but is undesirable because the free carbon which it contains impairs the insulating properties of the finished board or body, or its freedom from electrical conductivity.

As above indicated, the cellulose composition forming the body of the board or structure may vary more or less as to its class, or the source whence the cellulose is obtained, the binder employed and the relative proportions of cellulose and binder, the cellulose acetate composition lacquer or varnish used as a coating for such body, the choice of solvents therefor, the pigments or coloring matters employed, and the use or non-use of softening agents, as also their character and quantity as related to the cellulose acetate composition.

As a concrete example the following steps constitute a typical procedure:

1. A sheet or body is formed of pulp composition, comprising cellulose and gilsonite or other suitable and known binder, the proportion of which binder may vary within the range now usual in the art.

2. The sheet or body so formed is substantially freed of its liquid content, preferably by heavy pressure, and finally completely dried in any suitable way.

3. Any face or all faces of the board or body so dried is or are coated with the cellulose acetate varnish, lacquer, or composition, by spraying or dipping, by means of a brush, or otherwise, as found expedient in any given situation. If it be desired to impart any given color to the board or ultimate product, such coloring matter or pigment is incorporated in the cellulose acetate composition, and so applied to the surface or surfaces coated. Care should be taken that only sufficient of the cellulose acetate preparation to be used to form a film between the board or body and the surface or surfaces with which an element of a pressure device of any suitable type is later to contact. A film of approximately one one-

hundredth of an inch in thickness is usually sufficient.

4. This coating is allowed to dry, and the coated board or body is then subjected to 5 heavy pressure in any suitable press or pressure device capable of being heated in such portion or portions as come into contact with the coated face or faces of the board or body, so that said board or body shall be 10 subjected simultaneously to pressure and to heat, and so also that those portions of the board or body subjected to heat shall be prevented by the cellulose acetate coating from adhering to the heated surfaces. This

15 treatment is continued until the board or body is compacted to the desired density. The pressure is further maintained for a time, the steam or other heating agent is then cut off, and a cooling agent is substituted therefor in order to lower the temperature of the board or body while still under pressure and to prevent any warping or distortion of such board or body when relieved of pressure.

20 5. The compressed and dried board or body is now removed from the press, and its surface is finished by the use of sandpaper or emery cloth, or by rubbing with suitable abrading materials in the form of fine granules or powder and of successively finer 25 grades if need be, until a "flat" or "egg shell" finish be obtained; or if a highly polished surface is desired, buffing may be resorted to.

30 The prominent and essential feature of my invention consists in the application to the cellulose composition board or body, of a coating which is effective to prevent adhesion to contacting surfaces of a press or pressure device when the formed body is 35 subjected to pressure and heat, or when wrapped, packed, stored, or shipped.

40 By the method above set forth I produce an inexpensive insulating board or body of fine texture and great density, of high capacity of insulation against the passage of 45 electric current, of any desired color, and of fine finish appropriate to varied uses.

The invention here set forth is intended primarily for the production of boards or 50 slabs, but may be utilized in the production of bodies of various forms capable of being molded, dried, and compressed by apparatus suitable to such operation. The claims are intended to cover such bodies or products 55 whether in the form of boards, slabs, rods, bars, or other configuration, and are to be read with that understanding.

What I claim is:—

1. In the process of manufacture of electrical insulation boards or bodies having a base of cellulose with gilsonite or similar binder, the steps, which consist in applying to the formed and dried body a surface coating of cellulose acetate varnish or lacquer; permitting the same to dry; and sub-

jecting said body simultaneously to heat and pressure.

2. In the process of manufacture of electrical insulating boards or bodies having a base of cellulose with gilsonite or similar binder, the steps, which consist in applying to the formed and dried body a surface coating of cellulose acetate varnish or lacquer employing a suitable solvent; subjecting the body so coated simultaneously to heat and pressure; and finally cooling the same while maintaining the pressure; whereby said body is prevented from adhering to contacting bodies or surfaces during subsequent treatment, or after completion. 75

3. In the process of manufacturing electrical insulation bodies having a cellulose base, the steps, consisting in adding to a cellulose acetate varnish or lacquer suitable coloring matter and coating therewith such portion or portions of the formed and dried cellulose body as is or are to be exposed to heat and pressure in the process of completing said body; whereby such body is protected against adhesion to contacting surfaces during the process of completion, and the lacquer is caused to unite with the cellulose base and carry into the same the coloring matter. 80

4. The herein described method of producing electrical insulation boards and bodies, which consists in the following steps: (1) forming a mass of pulp composition comprising cellulose and gilsonite or similar binder, and of the general form and dimensions to be given the finished product; (2) removing from such mass its moisture content; (3) applying to any or all faces of the board or body so dried, a thin film or coating of cellulose acetate varnish or lacquer and permitting the same to dry; (4) subjecting the board or body after drying of the coating, to heavy pressure and to heat until the board or body is compacted to the desired density; (5) cooling the heated portions of the pressure device; and (6) relieving the board or body of pressure and removing it from the pressure device for final treatment or use. 95

5. The herein described method of producing electrical insulation boards and bodies, which consists in the following steps: (1) forming a mass of pulp composition comprising cellulose and gilsonite or similar binder, and of the general form and dimensions to be given the finished product; (2) removing from such mass its moisture content; (3) applying to any or all faces of the board or body so dried, a thin film or coating of cellulose acetate varnish or lacquer to which is added prior to its setting or drying a suitable pigment or coloring matter; (4) subjecting the board or body after drying of the coating to heavy pressure and to heat until the board or body is 100 105 110 115 120 125 130

compacted to the desired density; (5) cooling the heated portions of the pressure device; and (6) relieving the board or body of pressure and removing it from the pressure device for final treatment or use.

6. The herein described method of producing electrical insulation boards and bodies, which consists in the following steps: (1) forming a mass of pulp composition comprising cellulose and gilsonite or similar binder, and of the general form and dimensions to be given the finished product; (2) removing the moisture from such mass; (3) applying to any or all faces of the dried board or body a thin film or coating of cellulose acetate varnish or lacquer in which is incorporated a softening agent such as methyl ester of paratoluelsulphoneamide, and permitting the same to dry; (4) subjecting the board or body after drying of the coating, to heavy pressure and to heat until the board or body is compacted to the desired density; (5) cooling the heated portions of the pressure device; and (6) relieving the board or body of pressure and finally removing it from the pressure device.

7. As a new product or article of manufacture, an electrical insulating board comprising a body formed of cellulose and gilsonite or similar binder, dried and compressed, and having incorporated in its outer

surface or portion and united therewith, cellulose acetate varnish or lacquer.

8. As a new product or article of manufacture, an electrical insulating board comprising a body formed of cellulose and gilsonite or similar binder, dried and compressed, and having incorporated in its outer surface or portion and united therewith, cellulose acetate varnish or lacquer containing pigment or coloring matter.

9. As a new product or article of manufacture, an electrical insulating board or body, comprising a body formed of cellulose and gilsonite or similar binder, dried and compressed, and having incorporated in its exterior surface or portion and united therewith, cellulose acetate varnish or lacquer and a softening agent such as methyl ester of paratoluelsulphoneamide.

10. As a new product or article of manufacture, an electrical insulating board or body, comprising a body formed of cellulose and gilsonite or similar binder, dried and compressed, and having incorporated in its exterior surface or portion and united therewith, cellulose acetate varnish or lacquer containing pigment or coloring matter and a softening agent such as methyl ester of paratoluelsulphoneamide.

In testimony whereof I have signed my name to this specification.

DANIEL MANSON SUTHERLAND, Jr.
